Primary Examiner — John Windmuller*Assistant Examiner* — John R Yeh(74) *Attorney, Agent, or Firm* — Andrew W. Chu; Craft Chu PLLC(57) **CLAIM**

The ornamental design for a plunger with a handle, as shown and described.

DESCRIPTION

FIG. 1 is an upper perspective view of the plunger with a handle showing my design.

FIG. 2 is a front elevation view thereof;

FIG. 3 is a back elevation view thereof;

FIG. 4 is a side elevation view thereof;

FIG. 5 is an opposite side elevation view thereof; and,

FIG. 6 is a top plan view thereof.

The portions in broken lines are presented for illustrative purposes and form no part of the claimed design.
